SLEEVE SHORTENER

Leon Goldberg, New York, N. Y.

Application June 26, 1941, Serial No. 399,822

1 Claim. (Cl. 2—269)

This invention relates to garments and refers more particularly to an improved device associated with a garment sleeve for permitting of the shortening of a sleeve and the locking and retention of the same in a shortened condition.

It is a common expedient to roll back the cuffs, use elastic arm bands or employ other similar makeshift means to shorten shirt sleeves when a person is at work, but such methods are usually objectionable or inefficient. It is, therefore, the object of the present invention to incorporate in the sleeve structure adjacent the cuff, a simple and effective device by means of which the operation of shortening the sleeve and locking the same in a shortened condition may be accomplished with ease and facility and without the necessity of unbuttoning the cuffs or unduly marring the freshly laundered appearance of the sleeve and cuff.

As a further feature, the invention comprehends a sleeve shortening device of the indicated character which may be economically produced and incorporated in the sleeve structure without requiring alteration to the garment or appreciably increasing the cost of manufacture.

With the above enumerated and other objects in view, the invention is set forth in greater detail in the following specification and illustrated in the accompanying drawing, in which:

Fig. 1 is a perspective view illustrating a shirt sleeve with the cuff in the normal position with reference to the wearer's hand.

Fig. 2 is a similar view illustrating the sleeve in shortened locked condition by the shortening device.

Fig. 3 is an enlarged sectional view on the line 3—3 of Fig. 1 showing the sleeve in its normal position.

Fig. 4 is a sectional view on the line 4—4 of Fig. 2 showing the sleeve in its locked shortened condition.

Fig. 5 is an enlarged transverse sectional view taken approximately on the line 5—5 of Fig. 1.

Referring to the drawing by characters of reference, 10 designates the shirt sleeve and 11 the cuff which is normally disposed as shown in Figs. 1 and 3 in covering relation to the wrist of the wearer.

The device for shortening the sleeve and locking and retaining the cuff in a retracted relation as shown in Figs. 2 and 4 of the drawing, consists of a substantially rigid strip 12 of any

suitable material which is associated with the sleeve and extends upwardly from the juncture of the sleeve 10 with the cuff 11. The strip 12 is preferably secured permanently within the sleeve so that it is covered and concealed thereby and as herein illustrated, the strip is enclosed in a box pleat 13 which extends longitudinally upward from the juncture of the sleeve with the cuff 11 and which box pleat is retained in box formation by stitching 14 extending upwardly an appreciable distance beyond the length of the strip 12.

The strip may be adhesively secured in place or otherwise permanently secured and it is also to be understood that the strip may, if desired, be removably associated and releasably retained in place so that it may be separated from the shirt when the same is being laundered.

In use and operation, when the wearer desires to shorten the sleeve so as to raise the cuff from the wrist covering position shown in Fig. 1 to the retracted position shown in Fig. 2, the portion of the sleeve adjacent the cuff is folded inwardly and downwardly under the cuff to produce an annular return bend 15 thereby disposing the strip 12 between the return bend 15 and the cuff 11 so that the said strip underlies the cuff and locks and retains the sleeve in its shortened condition against accidental or unintentional downward movement. Due to the flexibility of the sleeve material and cuff and the looseness of the cuff when in wrist covering position, it is possible to swing the stiffening strip 12 to the reversely directed position shown in Figs. 2 and 4. After the sleeve is shortened and the cuff is retracted upwardly, the portion of the wearer's arm above the wrist being larger positively precludes any possibility of accidental downward movement of the cuff.

What is claimed is:

A sleeve shortening device including a relatively rigid elongated strip secured to and located medially of the width of the sleeve with the lesser dimension of the strip of appreciably smaller width than the width of the sleeve and with its greater dimension extending longitudinally of the sleeve and upwardly from the juncture of the cuff therewith for locking the lower portion of the sleeve in an upwardly retracted folded relation with the cuff surrounding the followed lower portion of the sleeve.

LEON GOLDBERG.

CERTIFICATE OF CORRECTION.

Patent No. 2,328,137.

August 31, 1943.

LEON GOLDBERG.

It is hereby certified that error appears in the printed specification of the above numbered patent requiring correction as follows: Page 1, second column, line 51, for "followed" read --folded--; and that the said Letters Patent should be read with this correction therein that the same may conform to the record of the case in the Patent Office.

Signed and sealed this 19th day of October, A. D. 1943.
